AUTOMATIC AIR-INTAKE FOR SUBMARINES, &c.

1,151,540.

Specification of Letters Patent.

Patented Aug. 24, 1915.

Application filed October 26, 1914. Serial No. 868,579.

To all whom it may concern:

Be it known that I, ALLEN HOAR, a citizen of the United States, residing at Long Beach, in the county of Los Angeles, State of California, have invented new and useful Improvements in Automatic Air-Intakes for Submarines, &c., of which the following is a specification.

This invention relates to automatic means for admitting atmospheric air to submarines and the like when running close to or on the surface; and the primary object of the invention is the provision of a simple and reliable mechanism for automatically admitting atmospheric air when the submarine is at the surface and for closing and preventing access of sea-water when the submarine is submerged.

I am aware that automatic and float controlled valves have heretofore been used for admitting atmospheric air to a submarine; and I do not seek to claim such a combination broadly in itself, seeking only to claim the specific combination and arrangement herein set forth.

The details of my invention are fully described in the following specification and are shown in preferred form in the accompanying drawings, in which—

Figure 1 is an elevation showing a submarine equipped with my air intake, and Fig. 2 is an enlarged section of the air intake mechanism itself.

In the drawings the numeral 10 designates the hull of a submarine and the numeral 11 designates an interior compartment thereof, such as the engine compartment having the engines 12 therein. The automatic atmospheric air intake is designated generally by the numeral 13. This air intake is preferably housed under a superstructure 14 into which air and sea water may have access as through apertures 15. The automatic air intake mechanism is exposed to sea or atmosphere, as the case may be; being mechanically and physically protected by the superstructure. The automatic intake includes an intake tube 20 at the upper end of which is placed a valve 21 adapted to control the opening at the upper

end of the tube. This valve 21 may be mounted upon a vertical valve stem 22 and may be pressed downwardly by a spring 23, or the valve may be seated by water pressure without the aid of the spring. The lower end of the valve stem 22 may connect with a piston 24 in a cylinder 25, the office of this piston and cylinder mechanism being to raise the valve off its seat and to hold the valve in its raised position against the action of the closing spring 23. A pipe 27 leads to the cylinder 25. This pipe has two branches 28 and 29 leading to valves 30 and 31, respectively. These valves may be of any suitable construction and are normally closed. Associated with each of the valves is a lever arm 34 or 35; and the movement of either of these arms in the direction indicated by the arrows will cause the opening of the corresponding valve. The arms 34 and 35 project into a vertical tubular guide 32 perforated so as to be open to the water; and a spherical float 33 vertically movable in the guide tube 32 will strike the arms 34 and 35 and raise the arm 34 or press the arm 35 down. In the normal condition of surface travel, water will not reach the float 33 and it will press down on the arm 35, causing the valve 31 to be opened. Opening of this valve will admit fluid pressure (air 80 pressure) from the pipe 36 to the pipe 29 and thence to the cylinder 25 to act against the piston 24 to raise the valve 21. If the submarine goes beneath the surface, the water will gradually rise under the superstructure and in the tubular guide 32, raising the float 33 until it strikes the arm 34, moving that arm upwardly and opening the valve 30, which will allow exhaust of air from the cylinder 25, allowing the valve 21 to close. The valve will remain seated until the submarine again rises to the surface and the float 33 lowers against the arm 35, allowing fluid pressure to enter the cylinder 25 to raise the valve 21.

In the lower part of the tube 20 there is a manually operable valve 40 which may be closed and opened by a hand wheel 41, for use in case the automatic valve should fail to operate. The air inlet tube 20 has a hori-

95

100

zontal offset 42 below the valve 40 communicating at 43 with the interior of the boat, at a point to one side of the hand wheel 41; so that, if the automatic valve fails to close, 5 and water enters through the air inlet, the entering water will not prevent access to the hand wheel 41 to close the valve 40. This is an important operating feature.

The features I wish to particularly emphasize are: (1) the accuracy and reliability of my mechanism, due to the fact that the float does not directly move the main valve but moves it through the medium of a fluid pressure mechanism which may be made as 10 powerful and positive as necessary to always insure proper closure of the valve; (2) the provision for hand operation to close the inlet in case the automatic mechanism fails to operate, said provision being made so 15 that the hand operating wheel can always be reached even when water is entering; and (3) the general simplicity of the whole 20 mechanism.

Having described my invention, I claim:

25 1. Atmospheric air intake mechanism for submarines and the like, comprising a vertical air inlet tube, an automatically actuated valve controlling the opening at the upper end of the tube, an offset portion at the 30 lower end of the tube communicating with the submarine interior to one side of the vertical line of the air inlet tube, and a manually operable valve controlling communication between the air inlet tube and 35 the offset portion.

2. Atmospheric air intake mechanism for submarines and the like, comprising a vertical air inlet tube, an automatically actuated valve controlling the opening at the upper end of the tube, an offset portion at the lower end of the tube communicating with the submarine interior to one side of the vertical line of the air inlet tube, and a manually operable valve controlling communication 40 between the air inlet tube and the offset portion, said valve having means of manual operation extending into the submarine interior immediately beneath the air inlet tube and to one side of the communication of the 45 offset with the submarine interior, substantially as described.

3. Atmospheric air intake mechanism for submarines and the like, comprising a vertical air inlet tube open to atmosphere at its 55 upper end, a horizontal offset communicating with the bottom end of said tube, said horizontal offset having communication with the submarine interior to a point horizontally removed from a point directly beneath 60 said tube, a valve controlling the communication at the bottom of said tube, and means for manually operating said valve extending into the submarine interior immediately beneath said tube, substantially as described.

4. Atmospheric air intake mechanism for 65 submarines and the like, comprising a vertical air inlet tube with an open upper end, a valve adapted to close said upper end, a cylinder arranged within said tube, a piston therein, a rod on which both said piston and 70 said valve are mounted, and float controlled means for admitting and exhausting fluid pressure to and from said cylinder.

5. Atmospheric air intake mechanism for 75 submarines and the like, comprising a vertical air inlet tube with an open upper end, a valve over the open upper end of said tube and adapted to close said upper end by downward movement, a vertical valve stem for said valve extending downwardly into 80 said tube, a compression spring above said valve tending to normally seat it and to close the upper end of the tube, a cylinder within said tube below the valve and arranged concentrically therewith, a piston in 85 said cylinder mounted upon said valve stem, and float controlled means to admit and exhaust fluid pressure to and from said cylinder below said piston to cause movement of said valve.

6. Atmospheric air intake mechanism for 90 submarines and the like, comprising a vertical air intake tube open to atmosphere at its upper end, a valve over the said open upper end adapted to close the same by 95 downward movement, a cylinder within said tube beneath the valve, a piston in said cylinder connected with said valve, float controlled means for admitting and exhausting fluid pressure to and from the cylinder, a horizontal offset communicating with said tube at its lower end and communicating with the submarine interior at a point horizontally removed from the vertical tube, a valve controlling said communication between the tube and offset, and means for 100 manually operating said valve extending into the submarine interior directly beneath said tube, substantially and for the purpose described.

7. Atmospheric air intake mechanism for 105 submarines and the like, comprising a vertical air intake tube open to atmosphere at its upper end, a valve over the said open upper end adapted to close the same by 110 downward movement, a compression spring above said valve tending to press the valve downwardly to close the open upper end of said tube, a valve stem projecting downwardly into said tube, a cylinder within the 115 tube concentrically below the valve, a piston in said cylinder mounted upon said valve stem, float controlled means for admitting and exhausting fluid pressure to and from the cylinder, a horizontal offset communicating with said tube at its lower end and communicating with the submarine interior at a point horizontally removed from 120 125

the vertical tube, a valve controlling said communication between the tube and offset, and means for manually operating said valve extending into the submarine interior
5 directly beneath said tube, substantially as and for the purpose described.

In witness that I claim the foregoing I

have hereunto subscribed my name this 19th day of October, 1914.

ALLEN HOAR.
